(57) **CLAIM**

The ornamental design for a turntable, as shown and described.

DESCRIPTION

The patent or application file contains at least one drawing executed in color. Copies of this patent or patent application publication with color drawings will be provided by the Office upon request and payment of the necessary fee.

FIG. 1 is a front, top, right side perspective view of a first embodiment of a turntable, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a front, top, right side perspective view of a second embodiment of a turntable, showing our new design;

FIG. 9 is a front elevational view thereof;

FIG. 10 is a rear elevational view thereof;

FIG. 11 is a top plan view thereof;

FIG. 12 is a bottom plan view thereof;

FIG. 13 is a right side elevational view thereof;

FIG. 14 is a left side elevational view thereof;

(Continued)

FIG. 15 is a front, top, right side perspective view of a third embodiment of a turntable, showing our new design;
 FIG. 16 is a front elevational view thereof;
 FIG. 17 is a rear elevational view thereof;
 FIG. 18 is a top plan view thereof;
 FIG. 19 is a bottom plan view thereof;
 FIG. 20 is a right side elevational view thereof;
 FIG. 21 is a left side elevational view thereof;
 FIG. 22 is a front, top, right side perspective view of a fourth embodiment of a turntable, showing our new design;
 FIG. 23 is a front elevational view thereof;
 FIG. 24 is a rear elevational view thereof;
 FIG. 25 is a top plan view thereof;
 FIG. 26 is a bottom plan view thereof;
 FIG. 27 is a right side elevational view thereof; and,
 FIG. 28 is a left side elevational view thereof.
